UNITED STATES PATENT OFFICE.

MELVIN E. DARE, OF MUSKEGON, MICHIGAN.

AEROPLANE.

1,319,211.

Specification of Letters Patent. Patented Oct. 21, 1919.

Application filed October 28, 1918. Serial No. 280,105.

To all whom it may concern:

Be it known that I, MELVIN E. DARE, a citizen of the United States, residing at Muskegon, in the county of Muskegon and State of Michigan, have invented new and useful Improvements in Aeroplanes, of which the following is a specification.

The present invention relates to aeroplanes; and its object is to provide means for increasing or decreasing the camber of the aeroplane's wings; and further, to provide means for simultaneously increasing the camber of either wing and decreasing the camber of the other; and further, to provide means for simultaneously increasing or decreasing the camber of both wings; and further, to provide means for changing the angle of incidence of either wing; and further, to provide means for effecting all these ends as may be desired.

This, and any other objects hereinafter appearing, are attained by, and the invention finds preferable embodiment in, the structure hereinafter described and illustrated by the accompanying drawings, in which:

Figure 1 is a view in perspective of an aeroplane, part of one of whose wings and a part of whose side are broken away;

Fig. 2 is a like view of the framework of one of the wings;

Fig. 3 is a detail view showing a rock connection;

Fig. 4 is a side view of one of the ribs of the wings;

Fig. 5 is a face view of the frame which carries the wing, showing its mounting, means for rocking the same, means for changing the camber of the wing, and connected parts;

Fig. 6 is a sectional view of certain parts taken on a plane corresponding to line 6-6 of Fig. 5;

Fig. 7 is a sectional view of certain parts taken on a plane corresponding to line 7-7 of Fig. 5; and

Fig. 8 is a diagrammatic view showing the means for controlling the cords or chains whereby the camber of the wings is changed.

In the structure chosen for illustration by the drawings and for detail description in the body of this specification, the aeroplane has the body 1 provided with the cockpit 2 containing the aeronaut's seat 3 and the hand-operated parts whereby the various

mechanisms hereinafter described are controlled. Within and at each side of the body 1 (and essentially a part thereof) is securely fixed a rigid support 4 (cruciform in the construction shown) on which is rockably mounted at 5 a frame 6 (kite-shaped in the form illustrated) on which frame is carried the wing 7. While the mechanism at only one side of the aeroplane is particularly shown, it is to be understood that the mechanisms on both sides are identical. This frame 6 may be rocked on its pivotal mounting 5, as by the gear 8 journaled extraneously of the wing (on the support 4) which gear meshes with the toothed segment 9 of the frame 6, the gear being rotated as by its sprocket wheel 10 on the gear's shaft, which sprocket wheel carries the chain indicated at 11 passing over the sprocket wheel 12 controlled by the hand lever 13. It will be seen that by swinging this hand lever the frame 6 and the wing carried thereon may be rocked on the pivot 5 to change the wing's angle of incidence, as may be desired.

The wing comprises essentially a forward member 14 and a rearward member 15, rockably connected together and each being rockable on axes extending longitudinally of the wing; and the wing may also comprise an inner portion 16 having said rockable members and an outer portion 17 which is rigid or essentially integral. As shown, the wing's inner ribs 18 and 19 (only two appearing in Fig. 2 for the sake of clearness) comprise forward members 20 and rearward members 21, the former being rockable on the wing's framework rod 22 and the latter on the similar rod 23, securely carried by the frame 6 near their inner ends. The outer ribs 24, 25 (only two being shown in Fig. 2) are carried by said framework rods. The rib members 20, 21 are rockably connected together by the bar or wing framework rod 26, whose outer end 27 is rockably connected at 28 to the outer rib 24. The inner or free end of this bar 26 may be raised or lowered, to increase or decrease the camber of the wing, by the rack 29 pivotally connected with the bar's inner end, the gear 30 meshing with the rack and being rotated one way or the other by the cords or sprocket chains indicated at 31, 32 passing over the sprocket wheel 33 on this gear's shaft.

Each rib member 20 and 21 being, in the construction shown, pivotally mounted, one of these members, as 20, is made extensible and contractible as by the slide bearings 34.

5 The frame 6 being rockably mounted concentrically with the gear 39, i. e. on its shaft 5, it will be seen that in whatever rocked position the frame 6 may be, the camber of the wings may be increased and decreased as desired.

10 In order that the camber of either wing may be increased and that of the other wing decreased simultaneously by the aeronaut and by one and by the same operation, and in order that the camber of both wings may be increased or decreased simultaneously and by one and the same operation, a lever 35 is fulcrumed at 36 and carries a drum 37 (shown in two sections) turnable by the 15 hand wheel 38: Cords or sprocket chains 31 and 32 are wound on the drum, the opposite ends of one cord (as 31) passing around one pair of sheaves 39, 39 to the sprocket wheels 33 (one on each side of the aeroplane) and 20 engaging said wheels in such manner as to turn them in one direction; while the opposite ends of the other cord or chain (as 32) pass around the other pair of sheaves 40, 40 and engage said sprocket wheels in such 25 manner as to turn them in the opposite direction, which end is effected by passing the cord 32 between the drum and sheaves 40, 40 as shown in Fig. 8. The two cords or 30 chains may be continuous, thus forming a band or belt carried by the drum, all the 35 sheaves and the two sprocket wheels 33 at the opposite sides of the aeroplane.

35 In order that the camber of both wings may be increased or decreased simultaneously, one pair of sheaves 39, 39 are pivoted on the lever on the opposite side of the lever's fulcrum 36 from the other pair of sheaves 40, 40, the two pairs being equidistant from such fulcrum. Thus, the camber 40 of both wings may be changed by swinging the lever forward or backward.

45 The covering of the wing may be continuous over the outer portion 17 of the wing and the rearward member 15 of the wing's inner portion 16, as shown in Fig. 1; but the coverings of the forward member of the inner portion of the wing should be arranged as shown in Fig. 4. The covering 41 overlying and being slideable on the covering 42 and the covering 42 overlying and being 50 slideable on the covering 43.

55 The corners of the frame 6 may be guided by pins 44, 45 extending through and bearing in arcuate slots 46, 47 in the support 4, and by the inner ends of the wing's framework rods 22, 23 extending through and bearing in the arcuate slots 48, 49 in said support; and the inner end of the bar 26 may extend 60 through the arcuate slot 50 in the frame 6.

65 The invention being intended to be point-

ed out in and by the claims, is not to be limited to or by details of construction shown or described.

What is claimed is:—

1. In an aeroplane; a wing comprising 70 forward and rearward members rockable on axes extending longitudinally of the wing and rockably connected together intermediate said axes; means for rocking said members. 75

2. In an aeroplane; a wing comprising 80 forward and rearward members rockable on axes extending longitudinally of the wing and rockably connected together intermediate said axes; means for rocking said members comprising a gear journaled extraneously of the wing, and a rack meshing with the gear and connected to at least one of said wing members.

3. In an aeroplane; a wing comprising 85 forward and rearward members pivotally mounted on axes extending longitudinally of the wing and pivotally connected together, at least one of said members being extensible and contractible in the forward 90 and rearward direction of the wing; means for rocking said members.

4. In an aeroplane; a wing comprising 95 forward and rearward members rockable on axes extending longitudinally of the wing and rockably connected together intermediate said axes; means connected to at least one of said members adjacent the rockable connection of said members for rocking said members. 100

5. In an aeroplane; a wing having an inner rib and an outer rib, the inner rib comprising forward and rearward members rockable on axes extending longitudinally of the wing and rockably connected together; a bar extending from the rockable connection of said members to and rockable on the outer rib; means for moving the free end of the bar adjacent the rockable connection of said members to change the camber of the wing. 105 110

6. In an aeroplane; a wing comprising 115 forward and rearward members rockable on axes extending longitudinally of the wing and rockably connected together; wing coverings for said members respectively, the covering for one said member overlying and being in slideable relation to the covering for the other member; means for rocking said members. 120

7. In an aeroplane; a wing having inner and outer portions, the inner portion comprising forward and rearward members interrelatively movable; a wing covering for said outer portion and said rearward member of said inner portion; a wing covering for said forward member of the inner portion, one of said coverings overlying and being in slideable relation to the other covering; means for rocking said members. 125 130

8. In an aeroplane; a pair of oppositely disposed wings each of which comprises forward and rearward members rockable on axes extending longitudinally of the wing and rockably connected intermediate said axes; means for simultaneously increasing the camber of either wing and decreasing that of the other. 45
9. In an aeroplane; a pair of oppositely disposed wings each of which comprises forward and rearward members rockable on axes extending longitudinally of the wing and rockably connected intermediate said axes; means for simultaneously increasing the camber of either wing and decreasing that of the other and for increasing or decreasing the camber of both wings simultaneously. 50
10. In an aeroplane; a pair of oppositely disposed wings each of which comprises forward and rearward parts adapted to be interrelatively moved to increase and decrease the camber of the wings; rotatable elements journaled extraneously of the wings; connections between said elements and the wings respectively for changing the camber of the wings by the rotation of said elements; a lever having a rotatable drum and two pairs of sheaves, the pairs being 55
11. In an aeroplane; a body; a frame rockably mounted on the body; means for rocking the frame; a wing comprising forward and rearward members rockable on the frame on axes extending longitudinally of the wing and rockably connected together; means for rocking said members. 60
12. In an aeroplane; a body; a frame rockably mounted on the body; means for rocking the frame; a wing comprising forward and rearward members rockable on the frame on axes extending longitudinally of the wing and rockably connected together; means for rocking said members comprising a gear journaled on the body concentrically with the rock axis of the frame and a rack meshing with the gear 55 and connected to at least one of said wing members. 65
13. In an aeroplane; a wing having inner and outer portions, the outer portion being rigid and the inner portion comprising forward and rearward parts adapted to be interrelatively moved to change the camber of said inner portion; means for so moving said parts. 70
14. In an aeroplane; a wing comprising forward and rearward members rockable on axes extending longitudinally of the wing and rockably connected together, one of said members comprising forward and rearward parts extensibly and contractibly connected in slidable relation; wing coverings for said parts and for the other of said members respectively, each covering overlving and being in slidable relation to the adjacent covering; means for rocking said members. 75
15. In an aeroplane; a body; a wing-supporting frame carried by the body in pivotal relation thereto; slide bearings intermediate the body and the frame and positioned one above, one below, one before and one behind the pivotal axis of the frame. 80
- In testimony whereof I have hereunto set my hand at Grand Rapids, Michigan, this 25th day of October, 1918.
- MELVIN E. DARE.
